ROBERT B. McLAUGHLIN, OF NEWTON, MASSACHUSETTS, ASSIGNEE TO UNITED PRINTING MACHINERY CO., OF BOSTON, MASSACHUSETTS, A CORPORATION OF MAINE.

TRIP MECHANISM FOR SHEET-FEEDERS.

1,077,889.

Specification of Letters Patent.

Patented Nov. 4, 1913.

Application filed May 25, 1910. Serial No. 563,270.

To all whom it may concern:

Be it known that I, ROBERT B. McLAUGHLIN, of Newton, in the county of Middlesex and State of Massachusetts, have invented certain new and useful Improvements in Trip Mechanism for Sheet-Feeders, of which the following is a specification.

This invention relates to sheet feeding mechanism, and its object is to provide im-

proved trip mechanism for rendering the feeding mechanism inactive when a sheet has been fed to a predetermined position.

As shown by the accompanying drawings the invention is combined with that type of sheet feeding mechanism known as combing mechanism, that is, mechanism by which the top sheets of a pile are separated successively from the pile and advanced one by one to other feeding means by which

the sheets are carried forward to a printing press or other machine. The action of combing and feeding means of this type is as follows. The top sheets of the pile are advanced by the combing mechanism at a relatively slow speed to a predetermined point where they are permitted to dwell for a brief period of time, after which they are engaged by coacting feed rolls which carry them forward at a relatively rapid

rate. To those familiar with this art it is well known that the action of combing means is far from positive and that the sheets in being combed toward the feed rolls become skewed more or less, depending upon the thickness, texture, and surface of the sheets. For this reason it is customary to associate with the combing means some means adapted to correct the skewing of the sheets before the sheets are engaged by the

feed rolls. The correcting according to the present invention is accomplished by controlling the combing devices independently of each other, two combing devices, one for each side edge of the sheet being provided.

The combing devices are arranged to rest by gravity upon the top of the pile and are continuously driven. Each combing device is subject to the action of automatic means by which it is retracted from operative position, and the retracting means for each of the combing devices is subject to independent control. The control of the retracting means is effected by sheet-actuated mem-

bers normally intersecting the path of the sheet and adapted to restrain the retract-

ing means until displaced from normal position. By this means the combing device acting upon the more advanced side of the sheet becomes retracted while the other combing device continues to act, the other 60 combing device being permitted to act until the lagging side of the sheet is advanced to the transverse plane of the aforesaid advanced portion.

Great difficulty is experienced in devising 65 sheet-actuated controlling devices whose action is sufficiently sensitive to respond to the action of relatively thin sheets. So called tension rolls are sometimes provided for engaging the forward edge of a sheet 70 on either side of a sheet-actuated controlling member for the purpose of maintaining sufficient tension upon the sheet to enable the sheet to displace the controlling member. Tension devices, however, materially 75 increase the cost of a feeding machine and are not always satisfactory because they sometimes fail to fulfil the requirements, and also occupy valuable space which is required for other mechanism. 80

The chief object of the present invention is to provide trip mechanism controlled by sheet-actuated members which are so sensitive in their action as to respond to the action of extremely thin sheets without 85 requiring tension devices or other equivalent means.

A second object of the invention is to so control and arrange the sheet-actuated controlling member as to utilize it as a gage for 90 the front edge of the paper, to positively position the edge of the paper in parallelism with the axes of the feed rolls.

Hitherto sheet-actuated controlling members have been arranged to act directly upon the trip mechanism, the friction or retardation of said controlling members depending upon the tension existing between them and the trip mechanism. In order to overcome as far as possible the friction or other cause of retarding the movement of the controlling members the present invention interposes an actuating element between said controlling members and the trip mechanism. The actuating element is adapted 95 to act when released so as to strike and move the trip mechanism to release the retracting means by which the combing devices are retracted. The relatively great effect of a blow as compared to a slow steady pressure 100 105 110

is so well known as to require no explanation. The actuating element for the trip mechanism is so related to the controlling members as to be initially held in retracted position by said controlling members and to be released when said controlling members are displaced by a sheet.

Since an actuating element which acts by striking a blow requires less motive force than one operated by a slow continuous force it is apparent that a relatively light motive force is required in order to produce the requisite blow. The actuating element forming a part of the present invention is subject to a relatively light tension and is so related to the sheet-actuated controlling members as to be held in retracted position by said members and to be released when said members are displaced. The degree of friction of the retracted actuating element upon the sheet-actuated controlling members is hardly appreciable, the sheet-actuated members being so proportioned and arranged with regard to leverage and the application of pressure as to be nearly, if not absolutely, free to respond to action of a sheet.

Referring now to the accompanying drawings forming a part of this specification, Figure 1 represents in vertical section that portion of a sheet feeder to which is attached controlling mechanism embodying one form of the present invention. Fig. 2 represents a side elevation on a smaller scale of a combing device which is controlled by the mechanism in Fig. 1. Fig. 3 represents a top plan view of the combing mechanism including a pair of combing devices. Fig. 4 represents a side elevation opposed with relation to Fig. 1 of the same elements of a sheet feeder. Fig. 5 represents a front elevation of the parts included in Fig. 4. Fig. 6 represents a transverse section and elevation of the trip mechanism. Fig. 7 represents a vertical section of the actuating element for the trip mechanism, and including a sheet-actuated controlling member and other mechanism. Fig. 8 represents an elevation of one of the sheet-actuated controlling members. Fig. 9 is a perspective view of the controlling portion of such member. Fig. 10 is a perspective view of the member which coacts with that shown by Fig. 9, and which strikes the blow by which the trip mechanism is moved. Fig. 11 is a perspective view of a holder by which the member shown in Fig. 9 is supported.

The same reference characters indicate the same parts wherever they occur.

Before proceeding to a description of the novel mechanism embodying the present invention a brief description of the sheet feeder will be given.

Referring first to Figs. 1 and 2 A indicates a pile of sheets which are to be fed. A

pair of combing devices such as the wheels 12 and 12' are arranged to rest upon the pile of sheets by reason of their gravity. The combing wheels are rotated continuously in the direction of the arrow in Fig. 2 so as to comb the top sheets of the pile to and over a ridge 13 formed by a bend in one or more plates 14. The action of the combing wheels causes the sheets to move slowly over the ridge and then to coactive feed rolls 15 and 16.

As shown by Figs. 2 and 3 the combing wheels are affixed upon separate shafts 17 and 17', said shafts being mounted respectively in rock-arms 18 and 18'. The rock-arms are affixed upon separate sleeves 19 and 19', each loosely mounted upon a continuously rotating shaft 20. As shown by Fig. 3 the shaft is rotated by a chain 21, said chain engaging a sprocket (not shown) affixed upon the shaft. The shaft is mounted in bearings 22 supported by suitable frame work. Each of the combing wheel shafts is provided with a sprocket such as that indicated at 23 in Fig. 2, and the shaft 20 is provided with sprockets such as that indicated at 24. Each sprocket 23 is connected with a sprocket 24 by a chain 25.

Each of the sleeves 19 and 19' is attached to a rock-arm, said rock-arms being indicated respectively at 26 and 26'. The rock-arms are pivotally connected to links 27 and 27' which extend forward and are pivotally connected to arms 28 and 28' affixed respectively to independently movable rock-shafts 29 and 29'. Each of the rock-shafts 29 and 29' also carries a fixed arm 30 and a loose member comprising an arm 31 and an arm 32.

The combing wheels are adapted to be raised independently of each other by rocking the sleeves 19 and 19', the raising of the wheels being effected by automatic means of which that for one combing wheel is a duplicate of the other. A description of the reTRACTING means for one combing wheel will, therefore, serve for both.

Referring now to Figs. 4 and 5 it will be seen that one end of a plunger 33 is pivotally connected to the arm 32 by a pivot stud 34. The other end of the plunger extends through a swiveled abutment 35 supported by the frame, this end of the plunger being screw threaded and provided with lock nuts 36 and a washer 37 arranged to abut against the member 35. A spring 38 is coiled about the plunger and compressed between the abutment 35 and a collar 39 on the plunger, the tension of the spring being adapted to actuate the arm 32 and thereby retract one of the combing wheels through the several connecting members described.

The arm 32 carries a roll 40 which is adapted to be engaged by a cam 41 for the purpose of compressing the spring 38

and setting the lifting mechanism in position to act again upon the combing mechanism. The cam 41 is affixed to a continuously driven shaft 42. When this cam compels the spring 38 it raises the free end of the arm 31. The arm 31 is held raised by a detent 44 and is provided with an anti-friction roll 43 which engages the detent. The detent is pivotally mounted upon a stud 45 affixed to the frame, and is formed with a recess adapted to receive the roll 43, and with a shoulder 46 adapted to engage the roll to restrain the lifting mechanism. The detent normally hangs suspended from its stud 45 and is held to one side of its center of gravity by the roll 43. As the roll rises it passes the shoulder 46 and enters the recess above the shoulder. The force of gravity causes the detent to swing so that the shoulder passes under the roll, in which position the detent is locked before the cam 41 leaves the roll 40. The locking of the detent is effected by a trip member 47 which is movable to and from the path of the lower end of the detent. This trip member is affixed to a rockshaft 48 mounted in bearings in the frame. The trip member and rockshaft are weighted in such manner that the trip member is moved by gravity into the path of the lower end of the detent, in which position it is shown by Fig. 1. When the lever 32 is released by the cam 41, the force of the spring 38 reacts upon the lever 32 and arm 31, tending to move the latter downwardly. The arm 31, however, is supported by the shoulder 46 which is in the path of the roll 43. The roll tends to displace the detent, but the latter is held against displacement by the trip member 47 which stands in the path of the lower end of the detent. The rockshaft 48 is provided with an arm 49 which carries an adjustable stop screw 50. This stop screw is adapted to abut against any convenient portion of the frame to determine the normal or locking position of the trip member. Mechanism hereinafter described is provided for turning the rockshaft 48 to retract the trip member 47 from the path of the detent so as to release the mechanism which lifts the combing wheels. Figs. 4 and 5 show the trip member retracted from the detent. It will be understood that the mechanism just described is disposed at one side of the machine and that similar mechanism is disposed at the other side of the machine, and that the two sets of mechanism are adapted to be controlled independently of each other, as usual, in order to correct any skewing of the sheet.

The two trips which control the two detents independently are affixed to separate independent rock-shafts 48, said rock-shafts as shown by Fig. 6 being in alinement with each other with their inner ends abutting in

a bearing 51. Each of the rock-shafts is provided with a plurality of abutments of the form of fingers 52 (see Figs. 6 and 7), which receive a blow from a striker to release the spring-actuated mechanism for lifting the combing device. The fingers 52 are arranged in a series across the line of feed to be employed one at a time according to the width of the sheets being fed.

When either rock-shaft 48 is rocked to disengage its trip 47 from the respective detent 44 the detent becomes replaced by and releases the arm 31 and permits the arm 32 to move in response to the tension of the spring 38. The arm 32 is provided with a projection 53 which abuts against a portion of the arm 30 thereby actuating the connecting mechanism by which the combing device is retracted. While the combing device is in retracted position a cam 54 on the cam shaft 42 engages a roll 55 at the free end of the arm 30 and maintains the combing device in retracted position while the cam 41 acts to restore the various members which are subject to the tension of the spring 38. The cam 54 finally releases the roll 55 thus permitting the combing device to drop upon the pile and resume its combing action.

The sheet controlled devices by which the trip mechanism is actuated are illustrated in detail by Fig. 1 and Figs. 7 to 11 inclusive. Referring first to Fig. 1, 56 indicates one of two sheet-actuated controlling members which normally intersect the path of the sheet moving upon the plate 14. The member 56, hereinafter termed a trigger, is affixed to a holder 57 (see Fig. 11). The holder 57 is pivotally mounted upon a transverse pin 58 by which it is connected to a stationary bracket 59. The bracket is adjustably mounted upon a transverse rod 60 affixed to the frame and is adapted to be affixed in any one of several positions upon said rod by a pin 61. The bracket may be moved along the rod to the position required by the width of the sheets being combed.

Affixed to the holder 57 by rivets or any other appropriate means is a block 62 (see Fig. 9). The block is formed with a central tooth 63 and with oppositely extending arms 64. The bracket 59 is formed with a socket to receive a striker 65. The socket also contains a spring 66 by which the striker is actuated. The striker is so arranged as to strike the free end of the finger or abutment 52 to which it is adjusted and to thereby rock the shaft 48 to effect retraction of the combing device.

Fig. 10 illustrates the striker in detail, the striker in this figure being inverted. It is formed of a cylindric rod and is cut away at one end to form a plain surface 67 and shoulder 68. A pin 69 extends transversely

through the striker and projects therefrom on both sides. The projecting portions of the pin 69 are arranged in longitudinal slots 70 in the bracket 59 and project beyond the exterior of the bracket. The block 62 is so mounted with relation to the striker 65 that the tooth 63 is adapted to engage the surface 67 of the striker and to be engaged by the shoulder 68.

10 As shown by Fig. 1 the pivot pin 58 is in the plane of the surface 67 and consequently the pressure of the shoulder 68 against the tooth 63 is radial with regard to the pivot pin. The tension of the striker therefore has no tendency to swing the trigger about its pivot when the trigger is in this position, but when the trigger is moved by a sheet the point of contact of the tooth 63 with the shoulder 68 falls below the pivot 58 and the tension of the striker therefore assists the sheet in advancing the trigger. The tooth 63 continues to drop as it swings about the pivot 58 until the striker is released thereby, whereupon the striker strikes a blow upon the abutment 52.

15 From the foregoing description it is obvious that the function of the trigger is to merely release the striker, the striker thereafter performing the function of actuating the trip mechanism. A relatively light spring 66 is sufficient for this purpose inasmuch as the striker attains momentum sufficient to actuate the trip mechanism. It is obvious that the resistance of the trigger 56 20 due to frictional engagement of the tooth 63 with the shoulder 68 is almost negligible in view of the light tension of the spring 66 and the relatively short radius of the tooth 63 with relation to the radius of the trigger.

25 Referring now to Figs. 7, 8, and 11 it will be seen that the holder 57 is formed with a transverse portion 71 which is arranged in the line of a yielding abutment in the form 30 of a spring follower 72. The follower is inserted in a socket in the bracket 59 and is normally projected by a spring 73 contained in the socket. Its function is to limit the initial movement of the sheet-actuated member so that said member will act as a gage 35 for the front edge of the sheet. The rear end of the follower projects beyond the rear of the bracket 59 and is provided with a nut 74 by which the forward movement of the follower is limited. When the trigger is 40 in its normal position as shown by Fig. 1 the transverse portion 71 is slightly removed from the follower, but when the trigger is so far displaced by a sheet as to release the 45 striker the portion 71 is moved into contact with the follower as shown by Fig. 7. The lower end of the trigger is bent to form a hook 75 which serves the purpose of a stop gage for the front edge of the sheet indicated by the letter *a*. It is now apparent

50 that the sheet after causing the retraction of the combing means is held against further forward movement by the stop gage 75. The sheet in approaching the trigger passes under a plate on the strip 76 arranged above the ridge plate 14 and separated therefrom only so far as to provide sufficient space for the sheet. The strip 76 and likewise the plate 14 is cut away in order to permit the trigger to extend therethrough. The trigger 55 after effecting retraction of the combing means and after serving as a gage for the sheet is raised out of the path of the sheet before the sheet is taken by the feed rolls 15 and 16. A rock-shaft 77 is mounted in stationary bearings in the frame and is provided with a gear segment 78. A lever 79 pivotally mounted upon a fulcrum stud 80 is formed with a gear segment 81 which coacts with the segment 78. The lever 79 carries a cam roll 82 which is adapted to be engaged by a cam 83 affixed upon the cam shaft 42. A spring 84 is connected to the lever 79, said spring having sufficient tension to rock the shaft 77 in one direction and maintain the 60 roll 82 in contact with the cam 83. The cam 83 is formed with a concentric surface 85, a slightly larger concentric surface 86 and a point 87 which projects beyond the circle of the surface 86. The cam rotating in the direction of the arrow permits the roll 82 to drop from the surface 86 to the surface 85 shortly after the sheet comes to a stop against the gages 75 and by the action of the lever 79 the shaft 77 is rocked in the direction of the arrow. A pin 88 extending radially from the rock-shaft engages one of the arms 64 of the block 62 thereby swinging the trigger to the extreme right hand position indicated by the dotted lines in Fig. 65 7. The stop gage 75 is thus removed from the path of the sheet and is held in this position for a brief period during which the rolls 16 are moved into engagement with the sheet lying upon the rolls 15. The shaft 89 upon which the rolls 15 are affixed rotates continuously in the direction indicated by an arrow, and the sheet is thus carried out by the holder.

70 The rolls 16 are carried by arms 90 secured upon a rock shaft 91. A cam arm 92 is also secured upon the shaft 91 and carries a cam roll 93 which is arranged to be engaged by a cam 94 on the shaft 42. A spring 95 connected to the arm holds the roll in engagement with the cam and by its tension the rolls are normally separated from the rolls 15. The cam 94 is so formed as to move the rolls 16 into active position at the appropriate time and to maintain them in 75 such position for a sufficient period of time to insure complete removal of the sheet.

80 After removal of the sheet the rolls are again elevated by the spring 95. After the removal of the sheet the point 87 of the cam 130

83 engages the roll 82 thereby turning the rock-shaft 77 in the opposite direction. The pin 88 carried by the rock-shaft then engages one end of the pin 69 which extends 5 through the striker 65, and by the action of the pin 88 the striker is retracted sufficiently to permit the trigger 56 to return to its initial position in which the tooth 63 moves upwardly into contact with the surface 67 of 10 the striker. The return of the trigger is effected by gravity but is assisted by the spring follower 72. When the lever 79 is released by the point 87 of the cam 83 the striker 65 is moved forward by spring 66 15 until the shoulder 68 engages the tooth 63. In this way the striker and trigger are restored to their initial positions ready to act whenever the trigger is again displaced by a succeeding sheet. The various members of 20 the trip mechanism are all arranged to automatically resume their initial positions when the trigger and striker are restored.

By reference to Figs. 5, 6, and 8 it will be seen that the rock-shaft 77 is provided with 25 a plurality of radial pins 88 which are respectively adjacent but slightly out of line with relation to the fingers 52 of the rock-shaft 48. The relative positions of the pins 88 and fingers 52 are such that when a striker 30 is adjusted transversely of the feeding mechanism to coact with one of the fingers 52 an arm 64 of the block 62 and one end of the pin 69 of the striker will be positioned respectively one in front of and the other 35 behind a pin 88. Any number of pins 88 and fingers 52 may be provided, but for practical purposes two of each for each trigger are usually sufficient to adapt the trip mechanism to wide or narrow sheets.

40 Having thus explained the nature of my said invention and described a way of constructing and using the same, although without attempting to set forth all of the forms in which it may be made or all of the modes 45 of its use, what I claim is:—

1. The combination with sheet-feeding means, means including an actuating spring for rendering said feeding means inactive, and means for restraining said spring-actuated means; of an abutment carried by said

restraining means whereby the latter may be moved to release said spring-actuated means, a striker adapted to engage said abutment, a spring for throwing said striker against said abutment to move said restraining means as aforesaid, and sheet-actuated means for controlling said striker, said sheet-actuated means and said striker having coactive portions adapted to hold said striker in restraint out of contact with said abutment, said sheet-actuated means being adapted to release said striker when the latter is out of contact as aforesaid, whereby said striker is adapted to acquire momentum under the influence of said spring before engaging said abutment. 55

2. The combination with sheet-feeding means, of a sheet-actuated member initially occupying the path of a sheet, means controlled by the sheet-actuated member for 70 rendering the feeding means inactive, a yielding abutment for limiting the operative movement of said sheet-actuated member, whereby said member becomes a stop gage for the sheet, and means for further moving 75 said member against its abutment to remove it from the path of the sheet.

3. The combination with sheet-feeding means, means including an operating spring for lifting said feeding means, and means 80 for restraining said lifting means; of a spring, means adapted to be actuated by said spring for actuating said restraining means to release said lifting means, means for holding said actuating means in restraint, said holding means being movable by a sheet for releasing said actuating means, a double-acting member movable in one direction for retracting said sheet-operated means from the path of the sheet, and 85 movable in the reverse direction for moving said actuating means to its retracted position, and means for operating said double-acting member. 90

In testimony whereof I have affixed my 95 signature, in presence of two witnesses.

ROBERT B. McLAUGHLIN.
